CAP FOR FLASKS OR THE LIKE

Filed April 16, 1927

INVENTOR
Charles Lamar
BY
Mark V. Drury, Attorney

UNITED STATES PATENT OFFICE.

CHARLES LAMAR, OF BROOKLYN, NEW YORK.

CAP FOR FLASKS OR THE LIKE.

Application filed April 16, 1927. Serial No. 184,194.

The present invention relates to flasks or bottles, such as thermos bottles or the like, and has for its object to provide a cap therefor which can be used both as a drinking cup or as a funnel to facilitate the filling of the bottle.

My invention will be fully understood by reference to the accompanying drawing which forms part of this specification and 10 in which similar reference characters denote corresponding parts, Fig. 1 being an elevation of a flask equipped with my improved cap which is shown in longitudinal section; Fig. 2 a perspective view of the 15 cap when used as a drinking cup; Fig. 3 shows the cap when used as a funnel and Fig. 4 a sectional view of a cap of modified construction.

Referring to the drawing 10 denotes a 20 metal flask which is provided with an externally threaded neck 10' to receive the metal cap and 11 denotes a cork or other stopper. The metal cap 12 is provided at one end with a threaded portion 12' to 25 screw on the threaded neck 10' of the flask and at its opposite end with an outwardly projecting hollow cylindrical extension 13 forming a nozzle of such diameter as to fit in the mouth of the neck 10' so that when 30 placed over the neck in inverted position with its nozzle 13 projecting inwardly through the mouth of the neck the cap 12 will serve as a funnel facilitating the filling 35 of the flask. When it is desired to use the cap as a drinking cup the stopper 11 is used to tightly close the nozzle.

Instead of using the stopper 11 the outer 40 end of the nozzle 13 may be provided with a lid 14 which may be hinged to a ring 15 slidably mounted on said nozzle as shown in Fig. 4.

When the cap is to be used as a funnel the lid 14 is swung open and moved together 45 with the ring 15 toward the inner end of the nozzle. When the cap is to be used as a drinking cup the ring is moved toward the outer end of the nozzle to bear against

the upturned edge 13' thereof permitting the lid to be swung into closed position. The lid 14 may be actuated by a spring (not 50 shown) which tends to swing it into closed position and may be provided with tightening means such as a rubber or cork disk 16.

Since various other modifications may be made in the construction of my cap without 55 departing from the principle of my invention I do not wish to restrict myself to the details described and shown.

What I claim is:

1. As an article of manufacture, a cap 60 for a flask having a threaded neck, said cap being adapted to be used interchangeably as a drinking cup and funnel, and being formed at one end with a threaded portion to screw on the threaded portion of said neck 65 and at the opposite end with an open ended nozzle to fit in the mouth portion of said neck, and means displaceably mounted on said nozzle for closing the latter when said cap is used as drinking cup. 70

2. As an article of manufacture, a cap for a flask having a threaded neck and adapted to be used interchangeably as a drinking cup and funnel, said cap being formed at one end with a threaded portion to screw on the 75 threaded portion of said neck and at the opposite end, with an open ended nozzle to fit in the mouth portion of said neck, a lid on the outer end of said nozzle and an annular member slidably mounted on said 80 nozzle to which said lid is hinged.

3. A combined drinking cup and funnel for a flask having a threaded neck portion comprising, a cap for said flask having an enlarged cup portion, and a reduced nozzle 85 arranged at one end of said cup portion, a threaded portion at the open end of said enlarged cup portion for engagement with said threaded neck portion, a lid on the outer end of said nozzle and an annular ring 90 slidably mounted on said nozzle to which said lid is hinged.

In testimony whereof I affix my signature.
CHARLES LAMAR.
